UNITED STATES PATENT OFFICE.

PAUL WITTECK, OF BUTLER, NEW JERSEY, ASSIGNOR TO THE BUTLER HARD RUBBER COMPANY, OF NEW YORK, N. Y.

DESIGN FOR A COMB.

SPECIFICATION forming part of Design No. 22,152, dated January 24, 1893.

Application filed November 14, 1892. Serial No. 452,006. Term of patent 7 years.

To all whom it may concern:

Be it known that I, PAUL WITTECK, a citizen of the United States, residing at Butler, in the county of Morris and State of New Jersey, have invented and produced a new and original Design for Combs, of which the following is a specification, reference being had to the accompanying drawings, which form a part of this specification.

10 This design relates to combs.

Figure 1 is a view representing one side of my comb. Fig. 2 is a similar view of the reverse side of the comb.

The obverse or front of the comb A has an ornamented panel, as shown in Fig. 1. The reverse side B is provided with an ornamented panel, as illustrated in Fig. 2.

I claim—

The design for a comb, substantially as shown and described.

In testimony whereof I affix my signature in presence of two witnesses.

PAUL WITTECK.
